INVENTOR:

William Stewart

United States Patent Office.

WILLIAM STEWART, OF STEUBENVILLE, OHIO.

Letters Patent No. 105,012, dated July 5, 1870.

IMPROVEMENT IN APPARATUS FOR GENERATING AND BURNING GAS.

The Schedule referred to in these Letters Patent and making part of the same.

I, WILLIAM STEWART, of the city of Steubenville, county of Jefferson and State of Ohio, have invented a new and useful Improvement in Apparatus for Generating and Burning Gas, produced from prepared benzole or gasoline, of which the following is a specification.

My invention consists in a hollow cylinder, made of cast metal or sheet metal, with the upper end concave forming a cup or bowl, and the lower end screwed on to the supply-pipe. From the inside of the cylinder a hole (or holes) is drilled, coming out near the center of the cup.

On the edge of the cup or cylinder, there is a projection, extending upward, widening toward the top, which serves as a gas-generator, being impinged upon by the gas from the hole in the cylinder. The projection may be made hollow with gas-jets on the top, (a single plate may be used if only a small quantity of light is required, the hole in the cup furnishing sufficient gas.) When the projection is made hollow, it is connected by an opening in the lower end with the opening in the cylinder.

The inner plate of the projection is curved toward the center of the cup or burner, and the extremity of the curved plate is perforated with holes or slots, or either.

The supply is attached to the lower end of the cylinder, and extends a few inches downward, and on it is the cock which regulates the supply. It is then bent upward and connected with the reservoir, which is placed to one side and above the level of the burner.

When lighting the burner for use, a very little fluid is let into the bowl of the cylinder, which is set on fire and immediately produces gas to continue the burning.

A is the cylinder.

B, the projection.

C C, gas-jets.

E, pipe to connect with supply.

G, hole in cup.

H, curved top of plate.

I claim—

The cylinder A, with the cup and hole, G, so arranged as to cause the gas-jet to impinge on the double plate B, the cavity between the two plates and cylinder being connected, and both acting as gas-generators.

WM. STEWART.
